 tion of New York

Application July 29, 1947, Serial No. 764,460

11 Claims. (Cl. 235—61.5)

1

This invention relates to gun fire control mechanism, and has particular reference to mechanism for controlling anti-aircraft guns in defense against direct aircraft attack, including dive attack and torpedo attack. This application is a continuation-in-part of copending application Serial No. 566,749, filed December 5, 1944, by applicant, now abandoned.

A dive attack may be defined as one in which the actual bomb discharging flight is down the line of sight of the attacking airplane, whereas the torpedo attack may be defined as one in which the torpedo launching flight is substantially horizontal. In either case, however, practically all of the action occurs in a single plane. There are usually three distinct phases to such attacks, first, the approach, which is generally along a horizontal straight line, second, the fast curve into the direct attack line, and third, the dive or torpedo attack, generally also straight.

Direct aircraft attacks are difficult to combat, and many methods have been advanced to meet them without satisfactory results. The two recognized methods of defense against such attacks include shooting at the target in its horizontal straight line approach, which is in practical, reasonably efficient use, and shooting on the down curve portion of the approach, where the curving flight is considered as though composed of a series of short flights on chordal lines, a method which has been proposed and which is the method to which this invention is directed.

In accordance with the present invention, mechanism is provided for laying anti-aircraft guns so as to place shell bursts along the path of an attacking plane while it is swinging into, or immediately after it has swung into, dive bomb or torpedo discharge position in its course, by predicting the dive angle from an observation of its flight in approaching the dive and quickly shifting from curved flight or chordal shooting to straight line or dive shooting.

The invention is based on the following theory: If an aircraft target is coming in on a straight line towards a gun, substantially all that is needed to know to fire at it, is the range and the range-rate in order to compute values of advance range for each shot placed at intervals down the line of sight, which in this case is the line of flight and the line of fire. Any airplane flying in the horizontal may suddenly swing into a curve and essay such a direct attack, and in that case, without the present invention, several wasted bursts will be placed along the expected line of flight before the control officer will have noted

the curve and by the time the firing orders are changed, the bomb will have been launched and the target plane will no longer be worth destroying. In order to plan a defense for such attack it is necessary for the control officer to know, as early as possible, that (1) a direct attack is beginning, and (2) the radius of curvature of the target swing towards the same. Co-target angle rate is known from the rate-computer of the tracking director and rate of change of the rate is known, also. Furthermore, it is known that at the completion of the target swing into the line of sight the co-target angle rate will be zero. This value is available from the rate computer. As a rule the bomb is released immediately the attacker enters the line of sight tangent to his swing. At this point, then, it is imperative that a shell be placed to meet him before he can release the bomb, and such a shell must obviously leave the gun while the attacker is back on the curve a distance corresponding to the time of flight of the shell. To know this point is to know when to shift to direct line-of-sight firing in order to lose no shots, and this is the crux of the invention. The point may be known by its co-target angle approaching the critical value of -90° (the co-target angle ϕ being negative for approaching targets, and positive for outgoing targets), and the instant when the target is at this point is shown by the invention, automatically switching the gun to direct fire, since at this instant the gun has taken the line of sight as its line of fire. Thereafter the fire is head-on into the target.

It will be seen that this provision for rapid transition of gun control from chordal shooting, which assumes that the curved path is a portion of a circle and that the flight is a series of chords of that circle, to substantially straight dive shooting during the dive, not only reduces the misses but also saves the valuable time heretofore expended in the attempt to recover the target in the line of sight from which it departed when it changed its course.

For a more complete understanding of the invention, reference may be had to the accompanying drawings, in which:

Figure 1 is a diagram of a typical dive attack; Figure 2 is an enlarged diagram of the curved flight portion of the diagram of Fig. 1; and, Fig. 3 illustrates a schematic drawing of the apparatus for solving the mathematical equations involved.

Inasmuch as torpedo plane attack has the same mathematical elements of dive attack, a description of the latter will suffice for both. In a highly

satisfactory type of apparatus for straight line tracking of targets, the operator trains his telescope on the target by means of control mechanism actuated by a control lever until the rate computer, actuated in accordance with the movements of the control lever assumes control of the telescope, which thereafter automatically follows the target as long as the latter maintains the same course and speed. Corrective motions with the control lever are thereafter necessary only to compensate for changes in course or speed of the target. The gun or guns are automatically controlled or otherwise actuated in accordance with the automatic calculations of the rate computer, and firing proceeds in the usual way. An example of this type of apparatus is disclosed in co-pending application No. 531,562, filed April 18, 1944, jointly by applicant and George Agins and Richard Y. Miner.

In using this apparatus for tracking a dive bomb or torpedo-carrying aerial target, the operator moves the control lever to make the necessary correction when the target leaves the straight path and enters upon a curved path preparatory to diving. This correction is a measure of the radius of curvature of the target path and causes the gun or guns to be adjusted accordingly so as to place bursts upon the curve path of the target. Meanwhile, the computer, owing to these corrective changes in input automatically prepares for subsequent straight line dive shooting so that when the target straightens out in a dive and the shifting mechanism of this invention assumes control, the firing changes smoothly and automatically from chordal shooting to dive shooting.

The theory of this operation is illustrated by the diagrams of Figs. 1 and 2. Referring to Fig. 1, numeral 10 designates the gun director, which may be mounted on a ship or other mount. The target, shown as an airplane at 11, has progressed along the straight horizontal line 12 to point 13, from which it has digressed to begin the curve to point 11. When the target was at point 13, its last point on the straight line 12, the co-target angle was ϕ , being the angle between line 17 from the director 10 to point 13 and a line 17' perpendicular to the original straight target course 12. It will be understood that in its course along line 12 up to point 13, ordinary straight flight anti-aircraft fire is conducted, but beyond this point the aforementioned chordal type of shooting is employed, further details of which may be had upon reference to co-pending application Serial No. 677,870, filed June 19, 1946, by applicant, now abandoned.

Referring to Fig. 2, it will be observed that the continuation of the curve beyond point 11 becomes tangent at point 15 to a line 18 extended from director 10 into which the target moves and which it follows after it straightens out from the curve 13, 11, 15. In order to hit the target in the region of point 15, the last instant at which the projectile may be fired is when the target is still at point 11. A projectile fired when the target has progressed to point 19, for example, will burst at some point 20 on the downwardly projected curve, after the target has left the curve and is travelling along straight line 18. It is for this reason that when the target has reached the critical point 11, chordal shooting must be quickly abandoned and dive attack technique instantly substituted. Thus if the shift to dive shooting is delayed until the target has straightened out at 15, a wide miss, to the

right of the target course shown in Fig. 2, will be registered. The next projectile burst will be well down on the straight line dive below point 15. Inasmuch as the bomb is usually released very soon after the target enters the straight line dive 18 at point 15, it is of utmost importance that the bursts be placed at the very beginning of the dive, i. e., at or near point 15.

As seen in Figs. 1 and 2, point 15 is the point of hit for two distinct positions of the target, one at point 11 on the curve and the other at a fictitious position 28 on the projected line of dive 18, because a target at point 28 reaches point 15 at the same instant in time that the target at point 11 reaches the point 15. Thus, when the target reaches point 11 it may be considered as being at point 28, insofar as firing is concerned.

The only known factors when the target is at point 11 are the co-target angle 22, being the angle between the line of sight 16 to the target and a line 16' from director 10 perpendicular to a tangent to the target course; present range R, line 16 from the director 10 to the target; elevation angle E; bearing angle B, and rate of change of co-target angle,

$$\frac{d\phi}{dt}$$

30 It will be observed that the rate of change of the co-target angle,

$$\frac{d\phi}{dt}$$

35 is being reduced as the target travels around the curve, from its value at point 11 to the zero value at the tangent point 15, since the target, when moving down the line of sight, has fixed co-target angle and hence no co-target angle rate.

40 But the distance from point 11 to point 15 is the distance through which the target will travel while the projectile is travelling to meet it. Therefore, the time interval of target travel from point 11 to point 15 is the same time interval called time of flight of the projectile from 10 to 15, T_f . The rate computer generates a value of

$$\frac{d\phi}{dt}$$

50 which matches the value of

$$\frac{d\phi_0}{dt}$$

the first time rate of change of observed co-target angle, when the target is flying on a straight course.

The difference,

$$\frac{d\phi_0}{dt} - \frac{d\phi}{dt} = \frac{dC}{dt}$$

60 is the first time rate of change of target course, where

$$\frac{d\phi}{dt}$$

65 is the generated co-target angle rate for linear flight, and

$$\frac{d\phi_0}{dt}$$

70 is the observed co-target angle rate for all types of observed flights.

From this value of

$$\frac{dC}{dt}$$

a correction to ϕ for prediction is obtained from the approximate relation

$$\Delta\phi = \frac{Tf}{2} \times \frac{dC}{dt} \quad (1)$$

and the proper value of ϕ_p for prediction is

$$\phi_p = \phi + \frac{Tf}{2} \times \frac{dC}{dt}$$

which with reference to Equation 1, may be expressed as

$$\phi_p = \phi + \Delta\phi \quad (2)$$

In the case of a dive attack down the line of sight, the final value of ϕ is -90° , hence a simple switch mechanism on the ϕ_p output shaft can detect the target's approach to this attack line and reduce the curvature correction $\Delta\phi$ to keep the predictions near the attack line without losing any time. Therefore, at this point the shift to dive firing technique should be made, the line 18 being fixed as the line of fire from this point on. By this arrangement, the dive line of the target will be set up in the computer of director 10 a sufficiently long period of time before the dive begins, to maintain constant bursts over the entire target path.

Referring to Fig. 3, a semi-diagrammatic illustration of the director 10 and the appurtenant parts of the mechanism of this invention, numeral 30 designates the usual stabilized telescope in the field of view of whose prism 31 the aerial target is observed. The control lever 32, pivoted for universal movement, introduces the rates to follow-up mechanism which causes the telescope to follow the target. The rate computer 33 operates with lever 32 and telescope 30 to compute and feed to the predictor 34 for the gun or guns 35 the electrical quantities equal to present range, R; target speed, S; the first time rate of change of target course

$$\frac{dC}{dt}$$

and also the mechanical quantities of generated co-target angle ϕ , and target plane tilt angle α . An example of such mechanism including the control lever 32 and the rate computer 33 for developing and delivering the aforementioned mechanical and electrical quantities to predictor 34 is disclosed in said copending application Serial No. 531,562, and is not claimed herein. Likewise the predictor 34, which feeds to the gun 35 or guns the results of the calculations and which also develops from R, S, and α the electrical quantity

$$\frac{1}{Tf}$$

the reciprocal of time of flight of projectile, is well understood and in accordance with standard practice. The predictor 34 may be constructed in the manner disclosed in copending application Serial No. 446,886, filed June 13, 1942, jointly by applicant and others.

Referring now to the mechanism for switching the rate computer 33 and guns from a curve chordal firing to dive firing operation in accordance with this invention, this mechanism is generally designated 36 and includes parts 37 to 68, inclusive. A conventional electronic power amplifier 37, such as that illustrated in diagram 15-10, page 222 of RCA Technical Series RC15 (1947) Receiving Tube Manual, is connected to computer 33 by wires 38 and receives therefrom and amplifies the electrical quantity equal to

$$\frac{dC}{dt}$$

the first time rate of change of target course, and is connected to a reversible type motor 39 by wires 40, for driving the same. Conventional damping means, not shown, are provided to stabilize the system.

The motor 39 drives brush 45 of potentiometer-multiplier 43 by means of the shaft 44, gears 49, the pinion 50' and the rack 51 carrying the brush 45. The potentiometer 43 is connected, as shown, with its brush 45 in series opposition with the

$$\frac{dC}{dt}$$

wires 38. The input to potentiometer 43 is connected to secondary winding 46 of scaling transformer 50, whose primary winding 48 is supplied by wires 47 with the aforementioned value

$$\frac{1}{Tf}$$

from the predictor 34. By reason of the winding ratio of transformer 50, a voltage proportional to

$$\frac{4}{Tf}$$

is supplied to the end taps of potentiometer 43. The output voltage of potentiometer 43 is the voltage across movable brush 45 and the center tap 52 of secondary winding 46 of transformer 50. It will be observed that because of the connections shown, the voltage proportional to

$$\frac{dC}{dt}$$

is supplied by wires 38 from the rate computer 33 in series opposition to the output voltage of potentiometer 43, and in series with the input terminals of amplifier 37.

The shaft of motor 39 is extended at 44' and connected to one side of mechanical differential 53, whose other input is supplied by shaft 54 from the rate computer 33 and is the mechanical value ϕ . The output shaft 57 of the differential 53 is connected to the roller contact 59 of a simple rotary switch 58 arranged to engage relatively stationary segmental contact 60 carried by disc 56. The initial spacing between contacts 59 and 60 may be adjusted by rotating disc 56 of switch 58, this adjustment being effected by a worm and wheel connection 56' from hand crank 55. This adjustment is made in order to preset switch mechanism 58 manually to operate when the value of ϕ_p reaches the predetermined value as read on dial 55'. Thus, when switch mechanism 58 is preset for dive attack, its contact roller 59 is automatically brought into engagement with contact 60 when the value of ϕ_p reaches -90° . Shaft 57 is extended at 57' to predictor 34 to continue to supply changing values of ϕ_p to the predictor 34 to modify the target deflection rate to gun 35. It will be understood herein and in the claims that the general term "target deflection rate" has the same meaning in the art as the more common term "gun orders."

Switch mechanism 58 is connected by wires 61 in series with manual switch 62 at the director 10, which is closed by the observer when he is satisfied that a dive attack is intended, and the second break in the circuit energized from battery 63 is closed by switch mechanism 58 as described. Also in series with switches 58 and 62 is a relay 64 having its armature 65 normally

held by spring 66 in engagement with stationary contact 67 to maintain the aforementioned

$$\frac{dC}{dt}$$

circuit to amplifier 37. Upon energization of relay 64 the armature 65 engages contact 68 and disengages contact 67 to open the

$$\frac{dC}{dt}$$

circuit which has the effect of reducing that value to zero, so that motor 39 reverses its direction to reduce the curvature correction $\Delta\phi$ to keep the value of ϕ_p near the attack line.

Motor 39 and its associated potentiometer 43, and amplifier 37 solve aforementioned Equation 1,

$$\Delta\phi = \frac{Tf}{2} \times \frac{dC}{dt}$$

in the following manner: The output voltage of potentiometer 43 is proportional to the product

$$\frac{2}{Tf} \times \Delta\phi$$

where $\Delta\phi$ is proportional to the angular displacement of movable contact 45 from its zero position opposite center tap 52 of the winding 46. The input voltage applied to amplifier 37 is the algebraic difference between the magnitudes of the

$$\frac{dC}{dt}$$

and the

$$\frac{2}{Tf} \Delta\phi$$

voltages, and this difference voltage is amplified by amplifier 37, and applied to motor 39, which drives movable contact 45 of potentiometer 43 to the position where the

$$\frac{2}{Tf} \times \Delta\phi$$

output voltage of the potentiometer 43 is equal in magnitude to the

$$\frac{dC}{dt}$$

voltage, and as the input voltage applied to amplifier 37 is then zero, motor 39 is deenergized, and Equation 1 is solved;

$$\frac{2}{Tf} \times \Delta\phi = \frac{dC}{dt} \quad (3)$$

Solving Equation 3 for $\Delta\phi$, results in Equation 1

$$\Delta\phi = \frac{Tf}{2} \times \frac{dC}{dt}$$

Equation 2, $\phi_p = \phi + \Delta\phi$, is solved in the following manner by mechanical differential 53: The quantity $\Delta\phi$ is supplied by shafting 44, 44' as an input value to mechanical differential 53, while the quantity ϕ is supplied by the rate computer 33 by means of shafting 54, as another input value to the mechanical differential 53. The output quantity ϕ_p of mechanical differential 53 is the sum of the input quantities $\Delta\phi$ and ϕ , and Equation 2 is solved.

As stated, hand crank 55 supplies the input quantity ϕ_A , the selected attack line con-target angle, and, with the dial 55', is provided in order that switch mechanism 58 may be preset manually to operate when the value of ϕ_p reaches the predetermined value as read on dial 55'. Value ϕ_A is approximately -90° for a dive attack and

if the curvature correction $\Delta\phi$ reaches a value which would make ϕ_p algebraically less than ϕ_A , then contacts 59 and 60 of switch 58 close and reduce the value of ϕ until $\phi_p = \phi_A$. The resulting intermittent opening and closing of contacts 59 and 60 of switch 58 reduce the value of $\Delta\phi$ just enough to keep ϕ_p approximately equal to ϕ_A .

In operation of the gun fire control mechanism of this invention, the observer or gun control officer operates control lever 32 and consequently rate computer 33 by keeping the target in view on the cross-hairs of the sighting unit 30, 31 to control the gun or guns 35 to place projectile bursts along the straight path 12 of the target, in accordance with known practice. If the observer perceives that the target may go into a dive, he closes manual switch 62 and gives the necessary orders for dive attack defense. Mechanism 36 continuously solves Equations 1 and 2, and when the value of ϕ_p reaches -90° switch 58 closes and energizes relay 64 to break the

$$\frac{dC}{dt}$$

25 circuit to mechanism 36.

Solution of Equation 2 by mechanism 36 determines the last instant that a curve or chordal shot can be made to hit the target, i. e., when the target is at point 11. Inasmuch as the distance from point 11 to point 15 is the distance through which the target travels while the projectile is traveling to meet it and when the shift is made at that instant, the dive attack firing along line 18 requires no further change in the

$$\frac{dC}{dt}$$

35 value. Hence, it is appropriate to cancel that value for corresponding unchanged supply to the guns, by breaking the circuits supplying it to the mechanism 36, which is accomplished by relay 64 in the manner described. It will be observed that the supply of the values of range, R, target speed, S, and target plane tilt, α , to predictor 34 is not affected by operation of mechanism 36, and these changing values are continued to be effectively supplied by rate computer 33 to predictor 34 during the dive attack.

When the dive attack defense is completed, the observer returns manual switch 62 to normally open position, which deenergizes relay 64 whose spring 66 causes armature 65 to restore the corresponding break in the

$$\frac{dC}{dt}$$

60 value supply to mechanism 36, for resumption of normal firing. It will be observed that even if there are changing values of Tf or

$$\frac{d\phi}{dt}$$

65 the corresponding mechanisms remain operative until the dive attack defense is completed as determined by opening of manual switch 62.

In the foregoing discussion, it is obvious that a dive line for the attacking airplane has been chosen which passes through the director 10 or, in other words, the dive is shown as being down the line of sight. It is of course realized that this type of dive is purely academic and was chosen merely because the discussion is thereby rendered more clear. In most dive attacks, a line is chosen, because of the ballistics of the bomb release, which passes over the director, rather than

through it. Such a dive line therefore leaves the curve 11-19-15 at a point above the point 15. However, the device operates similarly and the rates fixed in the predictor cause the guns independently of the director to follow the airplane in its dive, whatever straight line is chosen. A more accurate result can be obtained by using $\phi'p = \phi + k\Delta\phi$, for operation of the switch 53, where $k =$ about 1.3, to more accurately blend the bursts into line 18.

An important feature of the system of this invention is that an error in the assumption of dive attack, when none is going to take place, wastes no shots unless the target actually enters the turn into its dive, since the linear predictions are unaffected by the device. If target's turn leads to a dive attack on another ship, no shots are wasted if the other ship is beyond own ship, and a minimum of shooting time is wasted if other ship is between own ship and the attacking plane, since linear prediction is resumed as soon as $\Delta\phi$ reaches zero.

The system of this invention is possible because of the appropriate choice of coordinates used in the analysis of the problem. A dive attack, down the line of sight, is simply $\phi = -90^\circ$. A torpedo attack is $\phi = -90^\circ + L$, where L is the lead angle for the torpedo. In an overhead level bombing approach, $\phi = -E$, where E is the elevation angle. The device can also be applied to the angle α , which is unimportant in a line of sight attack, but which approaches 90° for an overhead attack. Other forms of attack on own ship may be described and coped with, with like simplicity, because of the polar nature of the coordinates used in the solution of the problem.

The anticipated method of attack of the target is coped with by manually presetting the value of ϕ_A , by means of hand crank 55, for the value of ϕ of the expected attack.

Although a preferred embodiment of the invention has been illustrated and described herein, it is to be understood that the invention is not limited thereby, but is susceptible of changes in form and detail within the scope of the appended claims.

I claim:

1. In an anti-aircraft gun fire control apparatus, including calculating mechanism for continuously developing quantities corresponding to the co-target angle between the line of sight to the target and a relatively fixed base line, first time rate of change of target course, time of flight of projectile and target deflection rate, and for supplying said target deflection rate quantity to the gun, the combination of means for multiplying the said first time rate of change of the target course and one-half the projectile time of flight quantities to produce the product thereof, motive means driven in accordance with said product, and means jointly driven by said motive means and in accordance with said co-target angle for modifying said target deflection rate quantity supplied to the gun.

2. In anti-aircraft gun fire control apparatus, including calculating mechanism for continuously developing a mechanical quantity corresponding to the co-target angle between the line of sight to the target and a relatively fixed base line and electrical quantities corresponding to the first time rate of change of target course time of flight of projectile and target deflection rate, and for supplying said target deflection rate quantity to the gun, the combination of means for multiplying the said first time rate

of change of the target course and one-half the projectile time of flight quantities to produce the product thereof, electrical motive means driven in accordance with said product, and means 5 jointly driven by said motive means and in accordance with said mechanical quantity for modifying said target deflection rate quantity supplied to the gun.

3. In anti-aircraft gun fire control apparatus, 10 including calculating mechanism for continuously developing quantities corresponding to the co-target angle between the line of sight to the target and a relatively fixed base line, first time rate of change of the target course, time of flight of projectile and target deflection rate, and for supplying said target deflection rate quantity to the gun, the combination of means for multiplying the said first time rate of change of the target course and one-half the projectile 15 time of flight quantities to produce the product thereof, motive means driven in accordance with said product, a normally closed switch interposed in said first time rate of change of target course quantity supply, means jointly driven by said motive means and in accordance with said co-target angle and operative to open said switch when said motive means stops, and operative connections between said last-named means and said mechanism for modifying the target deflection rate quantity supplied to the gun.

4. In anti-aircraft gun fire control apparatus, 20 including calculating mechanism for continuously developing quantities corresponding to the co-target angle between the line of sight to the target and a relatively fixed base line, first time rate of change of target course, time of flight of projectile and target deflection rate, and for supplying said target deflection rate quantity to the gun, the combination of means for multiplying the said first time rate of change of the target course and one-half the projectile time of flight quantities to produce the product thereof, motive means driven in accordance with said product, means jointly driven by said motive 25 means and in accordance with said co-target angle, and connections between said last-named means and said mechanism for modifying said target deflection rate quantity supplied to the gun.

5. In an anti-aircraft gun fire control apparatus, 30 including calculating mechanism for continuously developing and supplying quantities corresponding to the co-target angle between the line of sight to the target and a relatively fixed base line, first time rate of change of the target course and time of flight of projectile, the combination of means for multiplying the said first time rate of change of the target course and one-half the projectile time of flight quantities to produce the product thereof, motive means driven in accordance with said product, and operative connections between said motive means and said co-target angle supply for modifying the same.

6. In an anti-aircraft gun fire control apparatus, 35 including calculating mechanism for continuously developing and supplying quantities corresponding to the co-target angle between the line of sight to the target and a relatively fixed base line, first time rate of change of the target course and time of flight of projectile, the combination of means for multiplying the said first time rate of change of the target course and one-half the projectile time of flight quantities, to produce the product thereof, motive means driven in accordance with said product, a nor-

normally closed switch interposed between said first time rate of change of target course supply and said motive means, and means responsive to a predetermined movement of said motive means for opening said switch.

7. In anti-aircraft gun fire control apparatus, including calculating mechanism for continuously developing a mechanical quantity corresponding to the co-target angle between the line of sight to the target and a relatively fixed base line, and electrical quantities corresponding to the first time rate of change of the target course, time of flight of projectile and target deflection rate, and for supplying said target deflection rate quantity to the gun, the combination of means for multiplying the said first time rate of change of target course and one-half the projectile time of flight quantities to produce the product thereof, electrical motive means driven in accordance with said product, means jointly driven by said motive means and in accordance with said mechanical quantity, operative connections between said last-named means and said target deflection rate supply for modifying the same, a normally closed switch interposed in said first time rate of change of target course quantity supply, and means driven by said last-named means for opening said switch.

8. In an anti-aircraft gun fire control apparatus, including calculating mechanism for continuously developing a mechanical quantity corresponding to the co-target angle between the line of sight to the target and a relatively fixed base line, and electrical quantities corresponding to first time rate of change of target course, time of flight of projectile and target deflection rates, and for supplying said target deflection rate quantity to the gun, the combination of means energized by said electrical quantity corresponding to the first time rate of change of target course and responsive thereto, means energized by said electrical quantity equal to the projectile time of flight and responsive to one-half said value, means for multiplying the output electrical quantities of said two means to produce the product thereof including series opposition connections between the output of said multiplying means and said time rate of change of target course output of said calculating mechanism, a normally-closed switch interposed in said time rate of change of target course quantity supply, operative connections between said mechanical quantity supply and said target deflection rate supply for modifying the same, and means responsive to an algebraic sum of the output of said last-named means and said mechanical quantity for opening said switch.

9. In anti-aircraft gun fire control apparatus, including calculating mechanism for continuously developing a mechanical quantity corresponding to the co-target angle between the line of sight to the target and a relatively fixed base line, and electrical quantities corresponding to first time rate of change of target course, time of flight of projectile and target deflection rate, the combination of means supplying said target course quantity, a normally-closed switch interposed in said means, normally deenergized electromagnetic means operatively connected to said switch, electrical means for multiplying the said first time rate of change of the target course and one-half the projectile time of flight quantities to produce the product thereof, electrical motive means driven in accordance with said product, means jointly responsive to said motive means and said mechanical quantity for combining the

same, operative connections between said last-named means and said target rate supply for modifying the same, and operative connections between said last-named means and a normally open switch in circuit with said electromagnetic means for energizing said electromagnetic means to open said normally-closed switch.

10. In anti-aircraft gun fire control apparatus, including calculating mechanism for continuously developing a mechanical quantity corresponding to the co-target angle between the line of sight to the target and a relatively fixed base line, and electrical quantities corresponding to first time rate of change of target course, time of flight of projectile and target deflection rate, the combination of means supplying said target course quantity, a normally-closed switch interposed in said means, normally deenergized electromagnetic means operatively connected to said switch, electrical means for multiplying the said first time rate of change of the target course and one-half the projectile time of flight quantities to produce the product thereof, electrical motive means driven in accordance with said product, means jointly responsive to said motive means and said mechanical quantity for combining the same, operative connections between said last-named means and said target rate supply for modifying the same, operative connections between said last-named means and a normally open switch in circuit with said electromagnetic means for energizing said electromagnetic means to open said normally-closed switch, and means for adjusting the spacing between the contacts of said normally open switch.

11. In anti-aircraft gun fire control apparatus, including calculating mechanism for continuously developing a mechanical quantity corresponding to the co-target angle between the line of sight to the target and a relatively fixed base line, and electrical quantities corresponding to first time rate of change of target course, time of flight of projectile and target deflection rate, the combination of means supplying said target course quantity, a normally-closed switch interposed in said means, normally deenergized electromagnetic means operatively connected to said switch, electrical means for multiplying the said first time rate of change of the target course and one-half the projectile time of flight quantities to produce the product thereof, electrical motive means driven in accordance with said product, means jointly responsive to said motive means and said mechanical quantity for combining the same, operative connections between said last-named means and said target rate supply for modifying the same, operative connections between said last-named means and a normally open switch in circuit with said electromagnetic means for energizing said electromagnetic means to open said normally-closed switch, and a second normally open switch in the circuit of said first normally open switch and said electromagnetic means for rendering the first normally open switch effective to energize said electromagnetic means.
